Augusta A. Wolff.

UNITED STATES PATENT OFFICE

2,337,644

AIR CONDITIONING APPARATUS

John G. Caduff, Cleveland, Ohio

Application August 9, 1941, Serial No. 406,131

3 Claims. (Cl. 261—28)

This invention is a continuation in part of my pending application for "Air conditioning apparatus" Ser. No. 367,211 filed Nov. 26, 1940, and relates in particular to air conditioning apparatus for the conditioning of air in residences, which apparatus cooperate with hot air heating plants to effect heating of the conditioned air, sending such air through the air pipe lines of these plants into individual rooms and returning the air through cold air returns back into the air conditioning apparatus.

The general object of this invention is an improved air conditioning apparatus of the type referred to above, particularly adapted to be used in conjunction with existing conventional heating and air conditioning plants in residences and the like and readily incorporable therein to convert these plants to all year air conditioning systems.

Another object of this invention is an improved air conditioning apparatus of the type referred to above which is of relative small size and has its parts compactly arranged so that the apparatus occupies limited space and can readily be placed adjacent existing conventional heating plants in residences and incorporated in such heating plant systems to convert same to all year air conditioning systems.

A further object of this invention is the provision of a two part all year air condition unit including an individual heating plant and an individual air conditioning apparatus arranged adjacent to the heating plant and interconnected therewith to a unitary device of relative simple construction which can be provided and installed at low costs and is housed in a simple and attractive cabinet made of two oppositely arranged parts.

In addition, the invention has certain other marked superiorities which radically distinguish it from presently known structures. These improvements or superior characteristics embodying certain novel features of construction are clearly set forth in the following specification and the appended claims; and a preferred form of embodiment of the invention is hereinafter shown with reference to the accompanying drawings forming part of the specification.

In the drawings:

Fig. 1 is a central vertical section through an air conditioning apparatus built in accordance with the invention.

Fig. 2 is a perspective view of the air conditioning apparatus shown in Fig. 1, the view being

drawn to smaller scale and partly broken away to show the arrangement of the parts in the unit.

Fig. 3 is a sectional view through the air conditioning apparatus with the section taken on line 5 3—3 of Fig. 1.

Fig. 4 is a cross sectional view through the air conditioning apparatus with the section taken on line 4—4 of Fig. 1.

Fig. 5 is a sectional view through an all year air conditioning unit including a heating plant and an air conditioning apparatus of the type disclosed in Figs. 1 through 5.

Fig. 6 is a perspective view of the heating plant portion of the unit shown in Fig. 5; and

Fig. 7 is a perspective view of the air conditioning apparatus of the unit shown in Fig. 5.

Referring now to the exemplified form of the invention shown in Figs. 1 through 4 of the drawings, reference numeral 2 denotes an air conditioning apparatus housed in a substantially rectangularly shaped cabinet 3 including a base plate 4, front and rear walls 5 and 6, and side walls 7 and 8. Cabinet 3, by means of vertically disposed walls 9 which are arranged parallel to side walls 7 and 8 and formed with upwardly and outwardly sloping upper portions 10 contacting said side walls and secured thereto, is subdivided into three chambers, a central combined air washer and blower chamber 11 and two side chambers 12. In addition, cabinet 3 has arranged in its rear portion a motor chamber 14 formed by rear wall 5, a vertical wall 15 and a horizontal wall 16, which motor chamber houses an electric motor 17 of conventional design adapted to actuate the blower and spraying devices, as will be later described.

The combined air washer and blower chamber 11 extends over the entire height of cabinet 3 and houses in its upper portion a water spray arrangement 18 embodying horizontally mounted water pipes 19 with downwardly extended spray heads 20 and in its lower portion a blower housing 21 supported by means of U members 22 on base plate 4. The blower housing which has substantially circular shape and is of less width than the lower portion of chamber 11, encases a rotary blower device 23 of the so-called "squirrel cage" type which embodies oppositely arranged intakes openly communicating with the side chambers 12 through truncated cone-shaped ring members 24 aligned with openings in walls 9 and side walls 25 of housing 21, which latter, in addition, includes a rectangularly shaped outlet 26 extending outwardly through the front wall 5 of

cabinet 3. The side chambers 12 furthermore communicate with chamber 11 through rows of eliminators 27 formed of a series of angularly extended metal strips which are disposed in parallel relation inwardly of the side walls 1 and 8 and mounted in removable frames 28 in turn secured to walls 9.

The air to be conditioned enters air washer and blower chamber 11 at the top thereof through an air intake conduit 29 which has arranged therein a removable air filter 30, and hence flows through water spray arrangement 18 to and through eliminators 27, side chambers 12 and ring members 24 into the oppositely arranged intakes of blower device 23 from where the washed, filtered and cooled air is discharged through outlet 26. While passing through the air conditioning device, filter 30 removes the heavier floating particles from the air and the downwardly directed water jets of the water spray arrangement 18 wash and cool such air and, in addition, effect acceleration of the downward flow of the air for the purpose of facilitating de-humidification of the washed air by eliminators 27 positioned rectangularly to the direction of the flow of the washed and cooled air. The water spray arrangement 18 communicates through a water pipe 31 with the main water line (not shown) and is principally fed by recirculating water discharged from spray heads 20 and drippings of eliminators 27 passing into the lower portion of chamber 11. For such purpose, lower portion of chamber 11 is arranged directly below spray heads 20 to form a water reservoir 32 provided with an overflow pipe 33, which reservoir gathers water discharged from heads 20, cools same if so desired by means of a cooling unit 34 arranged therein and permits of recirculation of such water, as will be presently described.

Thus, electric motor 17, which by belt drive 35 effects rotation of rotary blower device 23, is coupled by a second belt drive 36 with a rotary pump 37, the inlet of which is in open communication with water reservoir 32 and the outlet 38 of which is coupled by piping 39 with water spray arrangement 18, all for the purpose of continuously circulating water from reservoir 32 to and through spray arrangement 18 back to the reservoir etc. In this process, water lost through evaporation or humidifying of the air to be conditioned is added through water pipe 31, the flow of such water through pipe 31 being controlled either automatically or manually according to well known practices in the art.

All air passing through blower housing 23, the housing 21 of which is encircled and covered by the water in reservoir 32, is continuously exposed to the cooling effect of the water in said reservoir, an arrangement which insures sufficient cooling of the air while passing through the air conditioning apparatus, particularly, when the water in reservoir 32 is cooled by cooling unit 34 as clearly shown in Fig. 4.

The described air conditioning apparatus which may readily be coupled to any conventional hot air heating plant, is particularly adapted for use in so-called two part all year air conditioning units, see Figs. 5 through 7. These figures show a unit 40 embodying a self-contained heating plant 41 arranged in a rectangularly shaped housing 42 with an air outlet 43 at its upper wall 44 and an air intake 44 in its rear wall 45, and an air conditioning apparatus 46 which is similar in construction to the structure disclosed in Figs. 1 through 4. The housing 42 of heating plant 75

41 and cabinet 47 of air conditioning apparatus 46 are equal in height and width to form a unitary structure in which plant 41 and apparatus 46 are placed adjacent to each other and rigidly secured to each other. To properly align housing 42 with cabinet 47, air intake 44 of said housing is sized to receive outlet 48 of air conditioning apparatus 46 and rear wall 45 of housing 42 has attached to its outer face a U-shaped perforated angle frame 50 sized to closely fit into the recess 54 of the front wall 55 of cabinet 47. This arrangement effects proper alignment of housing 42 and cabinet 47, when housing 42 and cabinet 47 are placed adjacent to each other and partly shifted into each other, and also permits proper securing of housing and cabinet to each other by screws 50' extended through holes 51 in cabinet 47 into threaded holes 52 in frame 50. The thus formed single structure includes a single inlet 53 at the top portion of cabinet 47 and a single outlet 43 extended from the upper wall of housing 42.

Having thus described my invention, what I claim is:

1. In an air conditioning apparatus a casing, a vertically arranged main compartment in said casing having an intake at its upper end and fluid-tightly closed at its lower end, closed side compartments in said casing arranged at opposite sides of said main compartment and in communication therewith substantially midway between its opposite ends, air washing means in the upper part of said main compartment, an overflow pipe in the lower part of said main compartment arranged to hold a body of water collected therein below the level of communication between said main compartment and the side compartments, a blower in said lower part of said main compartment having a fluid-tightly sealed housing, including inlets in communication with said side compartments only, submerged in the water in said main compartment and water feeding means for said air washing means including pumping means in communication with the water in the lower part of said main compartment to effect recirculation of water discharged from said air washing means into said lower part of said main compartment.

2. In an air conditioning apparatus a casing, a vertically arranged main compartment in said casing having an intake at its upper end and fluid-tightly sealed at its lower end, closed side compartments in said casing arranged at opposite sides of said main compartment and in communication therewith substantially midway between its opposite ends, air washing means with downwardly extending sprayer heads in the upper part of said main compartment, an overflow pipe in the lower part of said main compartment arranged to hold a body of water collected therein below the level of communication between said main compartment and said side compartments, a blower in said lower part of said main compartment having a fluid-tightly sealed housing, including inlets in communication with said side compartments, submerged in the water in said main compartment, and water feeding means for said air washing means including pumping means in communication with the water in said lower part of the main compartment to effect recirculation of water discharged from said air washing means into said lower part of said main compartment.

3. In an air conditioning apparatus a casing, a vertically arranged main compartment in said

casing having an intake at its upper end and fluid-tightly sealed at its lower end, closed side compartments in said casing arranged at opposite sides of said main compartment, communicating passages between said main compartment and said side compartments, air washing means in the upper part of said main compartment, dehumidifying means in said passages, a blower housing in the lower part of said compartment having intakes in communication only with said side compartments, an overflow pipe in the lower

5 part of said main compartment arranged to hold a body of water collected therein below the level of said communicating passages, and water feeding means for said air washing means including pumping means in communication with the water in said lower part of the main compartment to effect recirculation of water discharged from said air washing means into said lower part of said main compartment.

JOHN G. CADGFF.
